(57) **CLAIM**

The ornamental design for a field towel container, as shown and described.

DESCRIPTION

FIG. 1 is a perspective view of a field towel container showing my new design;

FIG. 2 is a left side elevational view thereof;

FIG. 3 is a right side elevational view thereof;

FIG. 4 is a bottom plan view thereof;

FIG. 5 is a top plan view thereof;

FIG. 6 is an end elevational view thereof; and,

FIG. 7 is an opposite end elevational view thereof.

The broken-line disclosure in the views is understood to indicate unclaimed subject matter forming no part of the claimed design.
